UNITED STATES PATENT OFFICE

162,686

CONTROL KNOB

Thorleif H. Petterson, Pasadena, Calif., assignor
to Beckman Instruments, Inc., a corporation of
California

Application November 17, 1949, Serial No. 6,101

Term of patent 7 years

(Cl. D26—1)

To all whom it may concern:

Be it known that I, Thorleif H. Petterson, a subject of Norway, residing at Pasadena, in the county of Los Angeles and State of California, have invented a new, original, and ornamental Design for a Control Knob, of which the following is a specification, reference being had to the accompanying drawing, forming part thereof, in which:

Fig. 1 is a top view of a control knob, showing my new design;

Fig. 2 is a side elevational view; and

Fig. 3 is a bottom view thereof.

I claim:

The ornamental design for a control knob, substantially as shown.

THORLEIF H. PETTERSON.
